DESIGN FOR AN ELECTRIC WREATH OR SIMILAR ARTICLE

David J. Kelman, Brooklyn, N. Y.

Application March 25, 1941, Serial No. 99,869

Term of patent 7 years

To all whom it may concern:

Be it known that David J. Kelman, a citizen of the United States and resident of Brooklyn, in the county of Kings and State of New York, has invented a new, original, and ornamental Design for Electric Wreaths or Similar Article, of which the following is a specification, reference being had to the accompanying drawing forming part thereof, in which,

Fig. 1 is a front elevation of an electric wreath embodying my new design; and

Fig. 2 is a top plan view thereof.

The dominant characterizing feature of my design resides in a wreath comprised of shirred light reflecting material helically arranged substantially as shown.

I claim:

The ornamental design for an electric wreath or similar article, substantially as shown and described.

DAVID J. KELMAN.
